UNITED STATES PATENT OFFICE.

BENJAMIN F. HEBER, OF SAN FRANCISCO, CALIFORNIA.

STREET-INDICATOR.

1,295,493.

Specification of Letters Patent.

Patented Feb. 25, 1919.

Application filed September 11, 1917. Serial No. 190,863.

To all whom it may concern:

Be it known that I, BENJAMIN F. HEBER, a citizen of the United States, residing at the city and county of San Francisco and State of California, have invented new and useful Improvements in Street-Indicators, of which the following is a specification.

This invention relates to a street indicator and particularly to a manually operated device for use in street cars and trains, which will visibly indicate the next street or stopping point.

One of the objects of the present invention is to provide a simple, compact device of the character described comprising a casing, and a cylindrical frame journaled in the casing which serves as a carrier for a renewable street or station chart, together with a manually controlled means for intermittently revolving the drum to expose the names on the chart in successive order through a reading aperture formed in the casing. Another object of the invention is to provide a novel spring-actuated driving mechanism, whereby the drum may be rotated, also a reversing mechanism to be employed in conjunction with the same; and, furthermore, to provide a driving connection which permits both longitudinal and rotary movement of the drum. Other objects will hereinafter appear.

The invention consists of the parts and the construction and combination of parts as hereinafter more fully described and claimed, having reference to the accompanying drawings, in which—

Figure 1 is a front view of a street indicator.

Fig. 2 is a central, longitudinal section through the same.

Fig. 3 is a cross section on line 3—3 of Fig. 2.

Fig. 4 is a cross section on line 4—4 of Fig. 2.

Referring to the drawings in detail, A indicates in general a rectangular-shaped housing constructed of sheet iron or other suitable material, in the forward side of which is formed an elongated reading aperture 2. Formed as an extension of the housing A is a secondary housing B, in which is mounted a spring-actuated driving mechanism consisting of a clock spring 3 which is carried by a shaft 4 journaled crosswise of the housing B; the clock spring being

provided with the usual form of pawl and ratchet 5 to permit the spring to be wound and the tension to be exerted to revolve shaft 4. Journaled crosswise of the housing is an arbor 6 and a shaft 7, and journaled at right angles to the shafts 4, 6 and 7 is a driving shaft 8. Secured upon the shaft 4 is a main driving gear 9, and intermeshing with said gear is a pair of pinions 10 and 11 which are secured upon the shafts 6 and 7, respectively.

Pivottally mounted within the housing above shaft 6 is an escapement lever 12, and secured on shaft 6, in alinement therewith, is a standard form of escapement wheel 13. 70 Connected with one side of the lever 12 is a spring 14 which normally holds the lever in the position shown, and connected with the opposite side of the lever is an operating cord 15 which may be extended to a point 75 within convenient reach of the operator.

Secured on the shaft 7 is a bevel gear 16, and secured on shaft 8 is a pair of bevel gears 17 and 18. Shaft 8 is slidably mounted in its bearings and longitudinal movement may be transmitted to same to bring either of the gears 17 or 18 into or out of mesh with the gear 16 by means of a shifting lever 19 which is also operated by the conductor or operator, and arranged after operation to be locked in position by a spring-actuated pawl 20. Mounted within the main housing A is a cylindrical frame consisting of two end members 21 and 22 which are tied together by rods 23. Surrounding the 90 cylindrical frame is a cover 24, constructed of wire screen or other suitable material, and adapted to be secured on the cylindrical frame exteriorly of the cover 24 and to be supported by said cover is a street chart 25. 95

One end of the cylinder is provided with a shaft 26, which is secured in the head 22 and extended out through one end of the housing A, being turnably and slidably mounted in said housing. Formed on the exterior end of said shaft is a handle 27 and forming a connection between the driving shaft 8 and the opposite end of the cylinder 21 is a disk 28. This disk is permanently secured on the shaft 8 and a driving connection between said disk and the drum is made by perforating the face of the disk, as at 29, to receive pointed projections 30 formed on the ends of the rods 23. The driving end of the drum is supported by the 110

shaft 8 and it is not only permitted to revolve about said shaft but it may also move longitudinally thereon. The drum is, however, under normal conditions held in driving engagement with the disk 28 by a spring 31 which is interposed between the head 21 and a collar 32 secured on the outer end of shaft 8.

In actual operation, if it is desired to partly rotate the cylinder carrying the street chart 25 to bring a certain street name into reading position with relation to the slot 2, it is only necessary to give the escapement lever a pull by means of the cord 15. This permits the tension of the spring 3 to revolve shaft 4 and the gear 9 secured thereto in the direction of the arrow. This rotation of the gear is transmitted through gears 10 and 11 to revolve the shafts 6 and 7, the revolving movement of shaft 6 being limited by the spacing of the teeth on the escapement wheel. The movement of gear 7 is, of course, transmitted through the bevel gear 16 to revolve either the gear 17 or 18 secured on shaft 8, the direction of rotation of said shaft depending entirely upon which gear happens to be in mesh.

The spacing of the street names on the chart and the distance between the teeth on the escapement wheel is such that one row of street names will be brought into register with the reading opening 2 each time the escapement lever is pulled; the rows of street names coming into position in successive order as they are encountered along the route. It is, therefore, possible for the conductor to bring any street or station name into position and thereby indicate to the passengers the name of the approaching street or station. The reversing mechanism, that is the gears 17 and 18, together with the shifting lever 19 employed, permits the rotation of shaft 8 to be changed when the end of a run has been reached. The cylinder will be intermittently rotated in the opposite direction upon the return journey and the street names will consequently be displayed in their successive order.

The street names may be arranged in a single row, if desired, or in three rows, as here shown. The block numbers may also be indicated on said map, as shown. For instance, "18 Webster" indicates to a passenger that the eighteen hundred block on which the car is traveling is being approached. It is also possible to indicate the names of the streets over which the car line passes by names and distinguish said names by different colors. For instance, the names "Geary" and "Market" show that the car first travels down Geary St. and then enters Market St. "Geary St.", for instance, may be painted in red upon a green background while "Market St." may be printed in green with a red background, or any other

suitable color. The names of all cross streets, such as "Webster", "Fillmore", "Steiner", etc., may also be colored to conform with the words "Geary" and "Market". If "Webster St." crosses "Geary St.", then it is obvious that "Webster" will be painted red on a green background. This shows that the car is still running on "Geary St." If the next street indicated shows green on a red background, then it immediately indicates to the passengers that the car has entered "Market St."

This variation in color may be extended to cover any number of streets and thereby serves as a positive indicator showing the name of the street upon which the car is traveling. All cross streets are displayed in successive order as they are approached in the main reading opening 2 and the color in which they are printed indicates the street upon which the car is traveling.

The disk 28, as previously described, forms a driving connection between the shaft 8 and the cylinder. If for any reason it is desired to change the position of the cylinder with relation to the driving mechanism it is only necessary to grasp the hand wheel 27 and pull the cylinder as a whole longitudinally against the tension of the spring 31. The pointed ends of the rods 30 are thereby pulled out of the recesses formed in the driving disk and the driving connection is broken. The cylinder may then be rotated to bring any street name desired into register with the reading opening and a coupling or driving connection between the shaft 8 and the cylinder is again formed by merely releasing the hand wheel. Such release permits the spring 31 to force the cylinder or the pointed ends 30 back into the recesses of the disk, thus permitting an intermittent rotation to be transmitted to the cylinder when the escapement is operated. The driving connection between the cylinder and the mechanism is also broken if a new street chart is to be inserted as it is then necessary to revolve the cylinder at least one or two revolutions while the old chart is being removed and a new one is replaced.

While any suitable means may be employed for the purpose of securing the chart to the cylinder, a simple form of securing means is shown in Figs. 2 and 4. This means consists of a bar 40 secured between the heads 21 and 22. This bar carries three or more spring-actuated clips 41. One end of the chart or sheet to be secured on the cylinder is merely slipped under one end of the clips. The cylinder is then rotated to fold the sheet completely around same and the free end is then inserted on the other side of the clips 41 and is thus quickly and securely placed in position.

The mechanism as a whole is in reality driven by the clock spring, but power from

said spring can only be transmitted when the escapement lever is manually operated by the conductor through the cord. It is also necessary for the conductor or operator 5 to manually operate the shifting mechanism. Therefore the essential control resides with the conductor and automatic operations such as have heretofore been relied upon to perform the functions here described are entirely eliminated, thus reducing the chances 10 of misinforming the traveling public by displaying wrong street names if the mechanism gets out of time or is otherwise affected.

15 The mechanism may be lighted either from the exterior or the interior for night use and the materials and finish of the several parts comprising the machine as a whole may be such as the experience and judgment 20 of the manufacturer may dictate.

Having thus described my invention, what I claim and desire to secure by Letters Patent is—

1. A street indicator comprising a casing 25 having a reading aperture formed therein, a cylinder within the casing supporting a street chart, a driving shaft, means for rotating said shaft, a coupling member between said shaft and the cylinder, and means 30 permitting longitudinal movement of the cylinder to release it with relation to the coupling and to permit the cylinder to be rotated independently of the coupling and the driving shaft.

35 2. A street indicator comprising a casing having a reading aperture formed therein, a cylinder within the casing supporting a street chart, a shaft secured in one end of the cylinder supporting said end of the 40 cylinder, said shaft being journaled in the casing and adapted to be moved longitudinally therein, a driving shaft supporting the opposite end of the cylinder, said cylinder being freely turnable and longitudinally 45 movable on the driving shaft, a coupling on the driving shaft adapted to form a driving connection between the shaft and the cylinder, and means for driving said shaft.

3. A street indicator comprising a casing 50 having a reading aperture formed therein, a cylinder within the casing supporting a street chart, a shaft secured in one end of the cylinder supporting said end of the cylinder, said shaft being journaled in the casing and adapted to be moved longitudinally 55 therein, a driving shaft supporting the opposite end of the cylinder, said cylinder being freely turnable and longitudinally movable on the driving shaft, a disk secured 60 on the driving shaft having a series of interspaced recesses formed in one side, pins on the cylinder adapted to be received by said recesses to form a driving connection 65 between the disk and the cylinder, a collar

spring interposed between said collar and the cylinder to normally maintain the cylinder pins in engagement with the recesses.

4. A street indicator comprising a casing 70 having a reading aperture formed therein, a cylinder within the casing supporting a street chart, a shaft secured in one end of the cylinder supporting said end of the cylinder, said shaft being journaled in the casing and adapted to be moved longitudinally 75 therein, a driving shaft supporting the opposite end of the cylinder, said cylinder being freely turnable and longitudinally movable on the driving shaft, a disk secured on the driving shaft having a series of interspaced recesses formed in one side, pins on the cylinder adapted to be received by said recesses to form a driving connection 80 between the disk and the cylinder, a collar on the end of the driving shaft, a spring interposed between said collar and the cylinder to normally maintain the cylinder pins 85 in engagement with the recesses, and means for moving the cylinder longitudinally to pull the pins out of driving engagement with the disk and to permit the cylinder to be rotated independently of the driving shaft.

5. A street indicator comprising a casing 90 having a reading aperture formed therein, a cylinder within the casing supporting a street chart, a driving shaft supporting the cylinder, a pair of interspaced bevel gears secured on the driving shaft, a second shaft journaled in the casing at right angles to the driving shaft, a bevel gear secured on 95 said shaft, means for moving the driving shaft longitudinally in either direction to bring one of the first named bevel gears into mesh with the last named gears, means for securing the driving shaft against longitudinal movement when either of the first named bevel gears are in mesh, and means for transmitting a partial rotary movement to the second shaft.

6. In a street car indicator, a shaft, a disk 100 rigid on the shaft and having perforations therein, means to drive the shaft, a cylinder having an end mounted on the shaft, pins on the cylinder engageable in said perforations of the disk, a coil spring secured at one end 105 to the shaft and having its other end abutting said end of the cylinder, and manual means to slide the cylinder on said shaft to disengage the pins thereof from the disk.

7. In a street car indicator, a longitudinally movable driving shaft, a cylinder supported at one end on said driving shaft, reversible driving means for said driving shaft, and means to reverse said driving means by sliding said driving shaft so as to 115 rotate the cylinder in all positions of the driving shaft.

8. In a street car indicator, driving means, a cylinder slidably connected to said driving means, means connected to the driving

means to couple the cylinder to said driving means, and means to slide the cylinder to release same from said driving means.

9. In a street car indicator, a slidable driving shaft, a cylinder connected to the driving shaft, coupling means between the cylinder and shaft, reversible means to drive the shaft, and means to slide the shaft so as to effect driving of the cylinder in all positions of the shaft.

10. In a street car indicator, a shaft, a cylinder having an end mounted on the shaft, a coupling member rigid on the shaft,

means borne by the cylinder to engage the coupling, reversible driving means for the shaft, and means to slide the shaft to reverse same so as to effect rotation of the cylinder according to the direction of rotation of the shaft.

In testimony whereof I have hereunto set my hand in the presence of two subscribing witnesses.

BENJAMIN F. HEBER.
